(57) **CLAIM**

The ornamental design for a padlock, as shown and described.

DESCRIPTION

FIG. 1 is a front perspective view of a padlock, showing our new design.

FIG. 2 is a rear perspective view thereof.

FIG. 3 is a front side elevation view thereof.

FIG. 4 is a back side elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings illustrate portions of the padlock which form no part of the claimed design.
